HAND TOOL FOR REPLACING FRONT WHEEL BEARINGS

John Robert Samsky, 4927 Miramar Ave.,
San Jose, Calif.

Filed Dec. 29, 1964, Ser. No. 83,201

Term of patent 3½ years

(Cl. D54—13)

FIG. 1 is a perspective view of a hand tool for replacing front wheel bearings showing my new design therefor.
FIG. 2 is a plan view of the same.

FIG. 3 is an end elevation of the tool as seen from the right in FIG. 2.

FIG. 4 is a plan view similar to that of FIG. 2 but showing the side opposite thereto.

FIG. 5 is a side elevation of FIG. 4, the opposite side of the tool being identical.

FIG. 6 is an end view of FIG. 4 as seen from the left end thereof.

FIG. 7 is a sectional view longitudinally of the tool as seen in FIGS. 2 and 4 to show the elevational configurations along that plane.

I claim:

The ornamental design for a hand tool for replacing front wheel bearings, as shown.
